ABSORPTION REFRIGERATING MACHINE

Earl F. Hubacker, Highland Park, Mich., assignor
to Borg-Warner Corporation, a corporation of
Illinois

Application September 25, 1935, Serial No. 41,996

17 Claims. (Cl. 62—5)

This invention relates to refrigerating machines of the absorption type; that is, to machines in which heat is employed for separating out in a generator an evaporable fluid which is condensed and thereafter evaporated at a lower pressure in an evaporator and from whence the fluid passes through an absorber and is returned again to the generator by increasing the pressure of the fluid to a pressure slightly in excess of the generator pressure.

An object of the invention is to build a machine of this type particularly in relatively small sizes, although the machine is not in any way limited to small sizes, that will operate continuously and automatically with any source of heat and that can be air-cooled.

Another object of the invention is to build an inexpensive machine of the above type by simplifying the elements thereof to such an extent as not to require many of the valves, pumps and controls heretofore found necessary in such machines.

Another object of the invention is to provide in such machines simple metering devices for transferring fluid between regions of different pressures and then for varying the amount of fluid transferred in accordance with the varying demand for refrigeration which is placed upon the system.

Another object of the invention is to provide a heat pump mechanism capable of operation by the source of heat employed for heating the fluid in the generator, the device being adapted to operate upon a thermosiphon principle to force liquid into the generator whenever the device is filled with liquid by the absorber.

Another object of the invention is to provide a heat exchange device adapted to cool weak liquor withdrawn from the generator by employing the circulating air supplied to the generator.

Another object of the invention is to provide an improved absorber where the refrigerant in the system may be absorbed by the weak liquor therein and wherein a continuous condition of turbulent motion is maintained.

Another object of the invention is to provide a simplified structure and compact arrangement of the elements employed in refrigerating systems of this type.

For a better understanding of the invention, reference may now be had to the accompanying drawings forming a part of this specification, in which:

Fig. 1 is a diagrammatical view of a refriger-

ating system embodying the principles of the invention;

Fig. 2 is a front view, partly in elevation and partly in cross-section, of a refrigerator suitable for household or domestic use and being equipped with the refrigerating system embracing the principles of the invention; and

Fig. 3 is a vertical sectional view of the lower part of the refrigerator illustrated by Fig. 2, taken substantially upon the line 3—3 of Fig. 2.

Referring particularly to the drawings, the numeral 10 illustrates generally a cabinet or box having an upper heat insulated refrigerating compartment 11 and a lower apparatus compartment 12. The refrigerating compartment has an inner liner 13 surrounded by material 14 of good heat insulating quality. Both the heat insulated compartment and the apparatus compartment have a unitary outer shell 16. A frame 15 is provided throughout the structure for supporting and holding together the various elements embraced therein. A door 17 is adapted to provide a closure member for the insulated compartment 11 and likewise the apparatus compartment has a door 18.

In the apparatus compartment, at one side of and near the rear of the latter, is disposed a generator 19 consisting of an inner combustion chamber shell 20, an outer shell 21, and a flue 22 forming a passage through the upper part of the two. The two shells are welded together at the lower extremities thereof to provide a closed generating chamber 23 internally thereof.

A shell 24, providing an accumulating chamber or accumulator 25, is located above the stack 22 in such position that the products of combustion from the inner shell 20 pass outwardly through the stack for heating the accumulator. The generator and the accumulator are connected by a conduit 28 extending from the vapor space in the upper part of the generator to the liquid space in the lower part of the accumulator. There is also a conduit 29 connecting the generator and the accumulator, with the lower end of the latter conduit disposed below the liquid level in the generator 19 and the upper end thereof being disposed in the accumulator in such position that excess liquid from the accumulator will flow through the conduit into the generator.

Both the generator and the accumulator are surrounded by a heat insulating casing 31 having a stack or outlet 32 connected with a larger stack 33 extending entirely across the back of the cabinet 10 and downwardly behind the ap-

paratus compartment 12 in such position as to provide an outlet upwardly along the back of the cabinet, both from the heat insulated generator 19 and the space within the apparatus compartment 12 thereabout. The products of combustion from the generator 19 therefore are adapted to pass upwardly through the stack 22, around the accumulator 25, out through the stack 32, and then into the region above the cabinet through the larger stack 33.

The generator 19 can be supplied with any kind of heat, as, for example, by heat from the oil burner or lamp 34 projecting into the lower part of the shell 20.

The generator 19 may be filled with any suitable absorbent and refrigerating fluids, as, for example, ammonia and water, and when these fluids are heated by the operation of the burner 34, the ammonia vapor from the generator will pass into the accumulator through the conduit 28, will pass through the accumulated liquid contained therein, and thence to the vapor space in the upper part thereof above the upper end of the tube 29. Any accumulated particles of liquid from the generator 19 will be collected in the liquid within the accumulator before the vapor passes into the vapor space thereabove.

From the top of the accumulator the ammonia vapor passes through an outlet conduit 36 into a rectifier 37, which is built either sloping or otherwise in such manner as to drain any water vapor condensed in the rectifier back into the accumulator 25. The rectifier, as illustrated, is simply a thin coil located somewhat above other parts of the apparatus in a region where it will be exposed to air already heated by other parts of the apparatus. This air, though, will be cool enough to sufficiently cool the rectifier to condense out the water vapor therein, inasmuch as the fluid in the rectifier is much hotter than the fluid in other parts of the apparatus which has to be cooled. From the rectifier 37 relatively pure ammonia vapor flows through a conduit 38 to a condenser 39 located in a lower region of the apparatus compartment 12, where the condenser will be exposed to cooler air from beneath the cabinet 10 which will rise through the condenser, the rectifier 37, and thence will pass outwardly through the stack 33. The liquid ammonia condensed by the condenser 39 passes upwardly through a liquid conduit 41 and is forced through a capillary expansion tube 42 into the vapor expansion space within an evaporator 43.

The evaporator 43 is located in the upper part of the cooling compartment 11 of the refrigerator and in such position as to cool the air therein by natural draft circulation. The evaporator 43 also is provided with shelves 44 in which ice trays can be located for freezing water into ice cubes, etc.

The conduit 41 passes from the apparatus compartment 12 to the refrigerating compartment 11 through a groove 46 formed in the door opening adjacent the front edge of the compartment in such manner that the evaporator 43 and the apparatus within the apparatus compartment 12 can be entirely removed from the cabinet 10 without disconnecting anything. The entire apparatus therefore can be welded into a single unit and inserted and removed from the cabinet without disconnecting any of the parts thereof.

The capillary tube or metering device 42 consists of a relatively small tube such as that indicated at 47, which is helically wound within a larger tube or casing 48 which can be welded between various parts of the apparatus where a

metering device is required. The tube 47 provides the only passage through the tube or casing 48.

When the liquid ammonia from the liquid line 41 is expanded and reduced in pressure by the metering device or capillary tube 42, it immediately reduces the temperature of the evaporator 43 by evaporation therein and provides ammonia vapor therein as a result of the heat absorbed from the evaporator and the cabinet. The ammonia vapor thus formed passes from the evaporator through a vapor conduit 49 positioned within the groove 46 alongside of the liquid line 41 and the opposite end of which is connected to the lower end of an absorber 51 located within the apparatus compartment 12 somewhat above the condenser 39. Also attached to the lower end of the absorber 51 is a metering device 52, adapted to discharge weak liquor from the generator 19 into the absorber from the end of a weak liquor conduit 53. The opposite end of the conduit 53 is provided with a spirally wound section indicated at 54, which is located between a spaced pair of baffles 56 and 57 and the inner edges of which contact with the lamp 34 and the lower edge of the generator 19 respectively, in such manner as to provide a controlled inlet for the air supply required by the lamp. The opposite end of the spirally wound section 54 is connected to the lower part of the generator 19 as at 57a in such manner as to withdraw water or weak liquor from the generator wherefrom practically all of the liquid ammonia has been separated by vaporization. The weak liquor flowing from the generator through the section 54 will be cooled sufficiently by the air supplied to the burner between the baffles 56 and 57 to be supplied to the absorber 51 through the metering device 52.

The absorber 51 is built of a long section of tubing, indicated at 58, which slopes upwardly away from the inlet from the conduit 49 and the weak liquid supply line 53. This tubing is covered with fins 59 disposed in spaced relation thereon to increase the heat exchange surface thereof. Weak liquor from the weak liquor supply 53 and discharged through the metering device 52 will practically fill the tube 58. This liquid will be continuously agitated by additional liquid supplied through the metering device 52 and by the ammonia vapor exhausted thereinto from the conduit 46 which is continuously absorbed by the weak liquor. As ammonia vapor flows from the evaporator 43 into the absorber 51, the pressure in the absorber will be lower than that in the evaporator. As this absorption process continues, the upper end of the tube 58 will be progressively filled with relatively strong liquor. This liquid will overflow through absorber outlet 61, check valve 62, and inlet tube 63, into the upper part of heat pump apparatus or generator-absorber 64. This apparatus comprises a casing or receiver 66 having a metering device 67 connected to the upper portion thereof for discharging weak liquor thereinto from a second weak liquor supply conduit 69. The latter conduit also has a spirally formed section 71 which is nested within the spirally formed section 54 of the weak liquor supply conduit 53 and is connected to the lower extremity of the generator 19, as is indicated at 72.

The conduit 69 and the metering device 67 are adapted to discharge small quantities of weak liquor into the upper part of the receiver or casing 66 for the purpose of absorbing any ammonia

vapor contained therein, whereby the pressure within the casing will be reduced to a value lower than the pressure within the absorber 51 and in which event liquid will flow from the absorber to the casing until the latter is substantially filled.

The casing 66 also has an automatic siphon 74 attached thereto, with one end of the siphon attached to the bottom of the casing and the other to the top thereof. The end attached to the bottom has an upwardly projecting loop 76 formed therein, and the upper end of which is positioned about where it is desired that the liquid level within the casing 66 should be limited. The opposite end of this loop connects with an upwardly inclined bend or heating unit 77 which projects through an opening 78 formed in the side of the generator 19 in such position that the bend can be inserted within the generator above the lamp. The opposite end of the bend communicates with the upper end of the casing 66 through a connecting section 79. When the pressure in the casing 66 is reduced to such an extent as to cause a surge of liquid from the absorber 51, the casing will be filled quickly to or above the level of the upper end of the bend 76. When liquid finally flows over the bend into the heating section 77, a siphon will be formed in the bend 76 which will continuously discharge liquid from the casing 66 to the heating section 77. As soon as any liquid flows into the heating section 77 above the lamp 34, some of the ammonia in the liquid will immediately vaporize and flow upwardly through the connecting section 79 into the upper part of the casing 66. This upward passage of vapor through the section 79 will at once lift the liquid in the section over the upper end thereof, and this, together with the siphon effect produced by the bend 76, will cause a continuous circulation of liquid from the lower part of the casing 66 to the upper part thereof. As this liquid circulates through the loop 77, more of the ammonia will be evaporated from the liquid therein until finally the pressure within the casing 66 caused by this vaporization of ammonia will exceed the pressure within the generator 19. When this condition is reached, substantially all of the liquid within the casing 66 will be discharged through conduit 81 and coil 82 into the accumulator 25. As the liquid level within the casing 66 falls below the lower extremity of the bend 77, there will be an unbalanced hydrostatic head within the siphon 76, and this will cause a reverse flow of liquid through the siphon from the bend 77 and into the casing 66, thereby emptying the siphon and the heating section 77 as the remainder of the liquid is forced from the casing 66 into the accumulator.

The end of the conduit 81 providing an outlet for the casing 66 is connected to the lower end of the casing with the end thereof projecting within the casing in such a way as to retain within the casing a small amount of liquid. This liquid is the liquid that is drained from the heating section 77 during the latter part of the flow from the casing 66 and consequently is practically a weak liquor as a result of the boiling of ammonia therefrom in the heating section 77. This small amount of weak liquor in the bottom of the casing 66 will tend immediately to absorb some of the high pressure gas within the casing 66 to reduce the pressure within the casing to provide a difference in pressure between the generator 19 and the casing so that liquid will flow through the metering device 67.

A check valve 84, located in the conduit 81, prevents the return flow of liquid from the con-

duit to the casing 66 after the discharge of the latter is completed and thus will permit a reduction in temperature and pressure within the casing 66 as a result of the weak liquor retained in the bottom of the casing and not discharged to the accumulator 25 by absorption of the high temperature and high pressure ammonia vapor therein. Inasmuch as there is only a small quantity of ammonia vapor to be absorbed, since no further vaporization of ammonia takes place after the coil 77 is emptied, the temperature and pressure of the casing 66 will be very quickly reduced to such an extent that a further charge of strong liquor will soon flow into the casing from the absorber, thus filling the casing and automatically repeating the cycle of operation previously described.

If it is desired to increase the time required for absorbing the ammonia within the casing 66, this may be done by adding fins to the exterior surface of the casing 66. These fins will rapidly reduce the temperature of the casing, and consequently some of the ammonia vapor in the casing will be condensed into liquid ammonia during the time that vaporous ammonia is being absorbed by the weak liquor introduced into the casing for the purpose of absorbing such ammonia vapor.

After the discharge of the casing 66 is completed, the coil 82 and part of the conduit 81 down to the check valve 84 will remain substantially filled with a rich liquor of ammonia and water, and this will be heated in the coil to a temperature substantially equal to the temperature maintained within the accumulator 25. The size of this coil can be apportioned in such a way as to hold practically all of the liquid discharged from the casing 66 by a single operation of the latter to the end that a new cold charge of rich liquor from the casing 66 will simply displace the previous charge contained within the coil 82. In this way a substantial reduction in the temperature and pressure within the generator and the accumulator which might be caused by the discharge of an appreciable quantity of cold liquid thereinto can be prevented.

A baffle, indicated at 86, may be employed across the bottom of the apparatus compartment 12, and this baffle may be provided with suitable openings therein so as to direct the air circulating through the apparatus compartment in contact with the parts which it is desired to cool, thus preventing the flow around these parts of a large amount of cooler air which would adversely affect the draft across the apparatus by reducing the temperature that could be maintained within the stack 33. The edges of this baffle may be secured to the frame 15 around the base of the apparatus compartment. A sloping baffle 85 also is employed above the apparatus for directing heated gases into the stack 33.

When once the burner 34 is lighted, the apparatus is adapted to operate as a continuous, non-mechanical ammonia and water absorption system. To control and regulate the amount of refrigeration performed by the system, a suitable pressure actuated valve or control 88 may be employed for the purpose of varying the amount of oil supplied from supply tank 89 to the lamp 34 through supply line 91, thereby varying the amount of heat absorbed by the generator 19 and the amount of liquid ammonia condensed by the condenser and supplied to the evaporator. The greater the amount of heat supplied, the greater will be the amount of ammonia vapor delivered to the condenser by the generator. The surface

of the condenser 39 being constant, it will be apparent that if a greater amount of ammonia vapor is delivered to the condenser, this ammonia vapor will have to be condensed at a relatively higher pressure, and under such circumstances this higher pressure will cause a greater amount of liquid to be delivered to the evaporator by the metering device 42. Not only this, but the rate of delivery of weak liquor by the metering devices 67 and 52 will be increased to increase correspondingly the amount of ammonia vapor absorbed in the absorber, and the rate at which the vapor pressure in the heat pump 64 will be reduced. When the demand for refrigeration upon the evaporator 43 is decreased, the amount of oil supplied to the burner 34 will be proportionally reduced by the operation of the aforesaid control and hence the amount of liquid supplied to the evaporator for vaporization purposes and of that supplied to the absorber and heat pump for absorption purposes will be correspondingly decreased. The control may be of the fluid actuated type having a bulb 92 applied directly to the evaporator, if desired, in such a position as to respond to the temperature of the shelves thereof and also may be positioned in such manner as to be affected by the circulating air within the compartment 11. Under such circumstances the amount of ammonia supplied to the evaporator by the generator will be affected both by the demand for refrigeration upon the evaporator shelves and in the interior of the compartment 11.

It will be apparent that while the amount of heat supplied by the lamp 34 may vary, the generator, as long as the lamp may be burning at all, will always supply liquid ammonia to the evaporator 43 and weak liquor to the absorber 51 and the heat pump 64, thus providing a machine that is at all times continuous in operation. It will, of course, also be apparent that the machine may be cycled, if this is considered desirable, by turning down the lamp so that no appreciable amount of heat is delivered thereby.

During the continuous operation of the apparatus, the heat pump 64 will operate automatically to discharge at intervals the liquid contained within the casing 66 from the low pressure side of the apparatus or the absorption and evaporation side to the high side of the apparatus or the generating and condensing side. This is done simply by first absorbing the ammonia vapor from within the casing 66 to provide a pressure lower than the absorber pressure, then filling the casing 66 with liquid until the liquid therein overflows and siphons into the heating coil 17 where ammonia vapor is immediately and automatically vaporized to provide a pressure within the casing 66 high enough to force all of the liquid therein into the high pressure side of the apparatus or generator. When this movement of liquid is completed, no further pressure will be generated in the casing 66 because no liquid will then be contained within the loop 77. The gas in the loop 77 will, of course, be continuously heated by the lamp 34, but the heating of such gas will not vary the pressure within the casing 66. Instead of this, the vapor in the casing will be absorbed to reduce the pressure therein even though some of the vapor is still being heated within the loop 77.

While the metering device 67 is never shut off by any mechanical operation, the metering of fluid from the generator to the casing 66 nevertheless is discontinued except when the pressure within the casing 66 is lower than that within 75

the generator. When the pressure in the casing 66 is higher than that in the generator during periods when the liquid is being discharged from the casing 66, there is such a slight difference in pressure across the metering device 67 that very little, if any, fluid will flow through the metering device in the direction opposite that in which weak liquor is adapted to flow.

It is not intended that the invention should be limited to the exact structure illustrated herein, this being shown merely for the purpose of providing a practical embodiment of the invention on which the appended claims are drawn to cover any of the forms, applications, modifications and embodiments in which the invention may appear.

I claim:

1. A refrigeration apparatus comprising a generator, heating means for said generator, means for varying the supply of heat applied to said generator, an evaporator and an absorber, said heat supply varying means being associated with said evaporator and operable responsive to the thermal conditions therein, means for maintaining said generator and said evaporator and said absorber at different pressures and for continuously supplying variable quantities of liquid from said generator to said evaporator and said absorber respectively in proportion to the amount of heat supplied to said generator and means operable responsive to said heating means for effecting the transfer of strong liquor from said absorber to said generator.

2. An apparatus for refrigeration comprising an absorber having an upwardly inclined passage, means for continuously supplying vaporous ammonia to the lower extremity of said passage, and means for continuously supplying water to the lower extremity of said passage, thereby to create a continuous turbulence within the fluid contained within said passage, the pressure in said absorber being maintained at a pressure lower than the pressure at the source of said vaporous ammonia.

3. An apparatus for refrigeration comprising a receiver and an absorber, said receiver being connected to said absorber for receiving strong liquor therefrom, a generator connected to said receiver and adapted to receive said strong liquor contained therein, and heat-exchanging means comprising a looped conduit having the opposite ends thereof attached to said receiver for increasing the pressure within said receiver to a value greater than the pressure in said generator when said receiver is substantially filled with said strong liquor.

4. An apparatus for refrigeration comprising a receiver and a generator, said receiver being adapted to be filled with strong liquor to be discharged into said generator, a fluid heating element attached to said receiver for receiving some of the liquid therefrom when said receiver is substantially filled, and means for withdrawing liquid from within said heating element as the liquid level falls within said receiver.

5. An apparatus for refrigeration comprising a heating element continuously subjected to a heat source and a receiver, a liquid siphon attached to said receiver for filling said heating element with liquid from said receiver when the level of the liquid therein rises to a predetermined level, and discharge means for said receiver for discharging the contents of the latter after said heating element is filled with liquid.

6. An apparatus for refrigeration comprising a strong liquor receiver and a heating element, and a reversible siphon connecting said receiver and

said heating element for filling said heating element when said receiver is filled and for emptying said heating element when said receiver is being emptied.

7. An apparatus for refrigeration comprising a generator having a source of heat for heating the same and an air inlet for supplying air to said source of heat, conduit means for withdrawing weak liquor from said generator, said conduit means being positioned in said inlet to be cooled by said air supplied to said source of heat.

8. A method of refrigeration which comprises withdrawing strong liquor from an absorber to fill a strong liquor receiver and when said strong liquor receiver is substantially filled withdrawing some of said liquid from said receiver and evaporating the same for expelling said strong liquor from said receiver and supplying weak liquor to said receiver for absorbing the evaporator liquid therein.

9. A method of refrigeration which comprises withdrawing strong liquor from an absorber to fill a strong liquor receiver and when said strong liquor receiver is substantially filled withdrawing some of said strong liquor from said receiver and evaporating the same for expelling said strong liquor from said receiver and when said strong liquor receiver is substantially empty returning to said receiver any remainder of the liquid withdrawn therefrom which is not evaporated during said liquid-expelling process.

10. An apparatus for refrigeration comprising a generator and an absorber having a strong liquor receiver connected therebetween, pressure increasing means associated with said receiver for discharging the strong liquor content thereof into said generator, means between said receiver and said absorber for preventing any flow of fluid from said receiver to said absorber during the discharge of said strong liquor from said receiver, said means for increasing the pressure within said receiver being adapted to simultaneously heat said generator.

11. An apparatus for refrigeration comprising a generator and an absorber having a receiver connected therebetween, the latter to be filled with strong liquor from said absorber, continuously operative means for heating a portion of said receiver for increasing the pressure of said receiver whereby the strong liquor content thereof is discharged into said generator, means for preventing said strong liquor from coming in contact with said portion of said receiver until said receiver is substantially filled with strong liquor, and means independent of said absorber for decreasing the fluid pressure in said receiver.

12. An apparatus for refrigeration comprising a generator and an absorber having a receiver connected therebetween, the latter to be filled with strong liquor from said absorber, means for heating a portion of said receiver for increasing the pressure of said receiver whereby the strong liquor content thereof is discharged into said generator, means for preventing said strong liquor from coming in contact with said portion of said receiver until said receiver is substantially filled with strong liquor, and means for supplying weak liquor from said generator to said receiver for absorbing the vaporous content thereof.

13. An apparatus for refrigeration comprising

a generator and an absorber having a receiver connected therebetween, the latter to be filled with strong liquor from said absorber, means for heating a portion of said receiver for increasing the pressure of said receiver whereby the strong liquor content thereof is discharged into said generator, means for preventing said strong liquor from coming in contact with said portion of said receiver until said receiver is substantially filled with strong liquor, and an unobstructed two-way passage of restricted cross section between said generator and the bottom of said absorber for continuously supplying a metered quantity of weak liquor from said generator to said absorber.

14. An apparatus for refrigeration comprising a generator, an absorber, and means for transferring strong liquor from said absorber to said generator, said transferring means comprising a receiver connected to said absorber for receiving strong liquor therefrom, a connection between said receiver and said generator for delivering strong liquor thereto, heating means for increasing the pressure in said receiver so as to force strong liquor into said generator, and means for reducing the pressure in said receiver below that of said absorber so as to permit the delivery of strong liquor from said absorber to said receiver, said last-mentioned means comprising means for delivering weak liquor to said receiver.

15. In an absorption system of the two pressure type, a generator, a continuously operative heating element therefor, an absorber, and means for transferring strong liquor from said absorber to said generator, said means comprising a receiver connected to said absorber for receiving strong liquor therefrom, a coil connected to said receiver so as to be supplied with strong liquor therefrom, said coil being heated by said heating element and being operable for effecting the transfer of strong liquor from said receiver to said generator and means for reducing the pressure in said receiver so as to permit the delivery of strong liquor from said absorber to said receiver.

16. In an absorption system of the two pressure type, a generator, a continuously operative heating element therefor, an absorber, a receiver connected to said absorber for receiving strong liquor therefrom, means for reducing the pressure in said receiver so as to permit the transfer of strong liquor from said absorber to said receiver, and means including a thermosiphon coil connected to said receiver so as to receive strong liquor therefrom and adapted to be heated by said heating element for effecting the transfer of strong liquor from said receiver to said generator.

17. In an absorption refrigerating system of the two pressure type and having an absorber and a generator, the method of transferring strong liquor from the absorber into the generator which comprises removing a quantity of strong liquor from said absorber and collecting such quantity in a receiver, heating a relatively small portion of said quantity of strong liquor for forcing the same into the generator and supplying weak liquor from said generator to said receiver for periodically reducing the pressure therein below that of said absorber.

EARL F. HUBACKER
